CAMPER UNIT FOR PICKUP TRUCK

Stewart E. Gardner, 2643 Vista Ornada,
Newport Beach, Calif. 92660

Filed May 6, 1974, Ser. No. 467,392

Term of patent 14 years

Int. Cl. D12—16

U.S. Cl. D12—156

FIG. 3

FIG. 4

FIG. 5

FIG. 1 is a perspective view showing the front, top, and left side of the camper unit for a pickup truck;
 FIG. 2 is a right side elevational view thereof;
 FIG. 3 is a rear elevational view thereof;
 FIG. 4 is a front elevational view thereof; and
 FIG. 5 is a top plan view thereof.

The undisclosed bottom is substantially plain and unornamented.

I claim:

The ornamental design for a camper unit for pickup truck, as shown and described.
